The ornamental design for a camper body, as shown and described.

DESCRIPTION

FIG. 1 is a front, left isometric view of a camper body, showing our new design, as mounted upon a vehicle, in condition of use;

FIG. 2 is a rear, top, right isometric view thereof;

FIG. 3 is a front elevation view of thereof;

FIG. 4 is a rear elevation view thereof;

FIG. 5 is a left side elevation view thereof, shown without the vehicle;

FIG. 6 is a right side elevation view thereof;

FIG. 7 is a top plan view of a camper body, showing our new design, as mounted upon a vehicle, in condition of use; and, FIG. 8 is a bottom plan view thereof.

The broken lines depicting a vehicle in FIGS. 1 through 4 and FIGS. 7 through 8 show environmental structure and form no part of the claimed design. The broken lines on the camper show portions of the camper body that form no part of the claimed design.
